UNITED STATES PATENT OFFICE.

MICHAEL I. GINSBURG, OF PHILADELPHIA, PENNSYLVANIA.

SLIP-JAW WRENCH.

1,391,251.

Specification of Letters Patent. Patented Sept. 20, 1921.

Application filed April 2, 1919, Serial No. 286,919. Renewed February 17, 1921. Serial No. 445,854.

To all whom it may concern:

Be it known that I, MICHAEL I. GINSBURG, a citizen of the United States, residing at Philadelphia, in the county of Philadelphia and State of Pennsylvania, have invented new and useful Improvements in Slip-Jaw Wrenches, of which the following is a specification.

My invention relates to a new and useful improvement in slip jaw wrenches, and has for its object to so construct a wrench of this description that while it will take the same hold upon a nut, bolt head or the like when turned in one direction, will automatically release its hold upon the object when swung in the reversed direction.

A further object of my invention is to provide novel and effective means for automatically locking the adjustable jaw, and a still further object of my invention is to so combine this locking means with the mechanism for adjusting the sliding jaw that said jaw will be locked or released by the ordinary manipulation of the handle.

With these ends in view, this invention consists in the details of construction and combination of elements, hereinafter set forth, and then specifically designated by the claim.

In order that those skilled in the art to which this invention appertains, may understand how to make and use the same, I will describe its construction in detail, referring by numerals to the accompanying drawings forming a part of this application, in which:—

Figure 1, is a top edge view of a wrench made in accordance with my improvement.

Fig. 2, is a side elevation of the wrench, the major portion of the stationary jaw and its shank being broken away to clearly show the mechanism.

Fig. 3, is a detail view of the adjusting nut, its bushing and pintle upon which they slide.

Fig. 4, is a view similar to Fig. 2 showing the handle and mechanism in the position assumed during the reverse movement, and

Fig. 5, is a bottom edge view of the wrench.

In carrying out my invention as here embodied, 1 represents the head of the wrench with which is formed the stationary jaw 2 and the shank 3, and in this head is formed a suitable channel way 4 in which slides the tail piece 5 of the movable jaw 6, the tail

piece and jaw being formed in one piece. Upon the rear edge of the tail piece is formed the sectional thread 7 with which meshes the thread of the adjusting nut 8, said adjusting nut being fitted upon a bushing 9.

10 represents a pintle having an enlarged portion 11 adapted to slide in the hole 12 formed in the head, and the upper end of this pintle is threaded to receive an internally threaded cap 13; both the enlarged portion of the pintle and the cap being slotted for the reception of a screw driver to facilitate the assembling of the device.

The pintle 10 passes through the bushing 9 of the adjusting nut and through the shoulder 14 into the recess 15 in which is located the coil spring 16, so that this spring will be confined between the shoulder and the cap 13 when the latter is threaded upon the pintle, thereby normally holding the pintle and adjusting nut in the elevated position shown in Fig. 2, and as the tail piece of the movable jaw meshes with said nut this movable jaw will also be normally held in the position shown in Fig. 2.

17 represents the handle of the wrench, the inner end of which projects into the recess 18 formed in the shank 3 and is pivoted therein at 19 so as to have a limited swinging movement independent of the body of the wrench.

20 represents a locking dog which is pivoted at 21 to the inner end of the handle at a sufficient distance from the pivot point 19 to cause it to have sufficient movement to slide back and forward through the guideway 22, its inner end passing beneath the head of the bushing 9 when the handle is in the position shown in Fig. 2 and passing from beneath said head when the handle is in the position shown in Fig. 4 for the purpose hereinafter set forth.

From this description the operation of my improved wrench will be obviously as follows:—

The movable jaw may be adjusted by the revolving of the adjusting nut 8 so as to adapt the jaws of the wrench to any size nut or bolt head or other work within its limit.

When by applying the jaws to a nut and drawing upon the handle in the direction of the arrow in Fig. 2 the power may be applied to set up or back off the nut to

which the jaws are applied, since the locking dog prevents the downward movement of the adjusting nut 8 and consequently the sliding of the movable jaw 6.

5 When it is desired to take a new hold upon the nut or other work, a reversed movement of the handle will draw the locking dog from beneath the bushing 9 and permit the movable jaw to slide away from 10 the stationary jaw, drawing down the adjusting nut and compressing the spring 16. Thus it will be seen that the wrench will have the effect of a ratchet wrench since the 15 jaws will be permitted to slide over the largest diameter of the nut to which it is applied when taking a fresh hold thereon and yet be securely held upon the smaller diameter when this nut is being turned.

If found desirable the shank 3 may be extended to form a handle and a separate lever pivoted thereto for actuating the locking dog.

Of course I do not wish to be limited to the exact details of construction as herein shown, as these may be varied within the

limits of the appended claim without departing from the spirit of my invention.

Having thus fully described my invention, what I claim as new and useful is:—

In a wrench of the character described, a 30 head having a stationary jaw and a shank formed therewith, a movable jaw having a tail piece formed therewith adapted to slide in the head, a sectional thread formed upon the tail piece, an adjusting nut meshing 35 with said sectional thread, a bushing fitted to the adjusting nut, a sliding pintle passing through the head and the bushing of the adjusting nut, a cap secured upon one end of the pintle, shoulders formed within 40 the head, a spring confined between said cap and shoulders, a handle pivoted within the shank, and a locking bolt pivoted to the handle in such manner as to pass into and out of engagement with the bushing of the 45 adjusting nut when the handle is swung to and fro.

In testimony whereof, I have hereunto affixed my signature.

MICHAEL I. GINSBURG.
